W. B. Weaver,

UNITED STATES PATENT OFFICE.

WARREN B. WEAVER, OF LAKELAND, FLORIDA.

SASH-LOCK.

997,876.

Specification of Letters Patent. Patented July 11, 1911.

Application filed January 18, 1910. Serial No. 538,590.

To all whom it may concern:

Be it known that I, WARREN B. WEAVER, a citizen of the United States, residing at Lakeland, in the county of Polk and State 5 of Florida, have invented a new and useful Improvement in Sash-Locks, of which the following is a specification.

This invention relates to certain new and useful improvements in my former patent 10 for sash lock, granted to me November 17, 1903, No. 744,654, the object being to provide means for holding the locking bolt in an unlocked position in order to allow the sash to move freely within the frame.

15 Another object of my invention is to improve the general construction of the sash lock so as to provide a lock which is exceedingly simple and cheap in construction and one in which the bolt is so mounted that 20 the same will be held in its proper position without any danger of the same working loose in any way.

A still further object of my invention is to provide a locking bolt with a bifurcated 25 inner end in which is pivotally mounted a locking member which is adapted to be swung upwardly so as to engage the casing when the same is moved into an unlocked position in order to hold the same out of 30 engagement with the window frame.

Still another object of my invention is to provide a sash lock in which the sliding bolt extends inwardly through the side bar of the sash into a convenient position for 35 operating the same, the locking member being so mounted in the bolt that when the bolt is locked into an inoperative position by simply pressing upwardly on the end of the locking member the bolt will be released so 40 as to lock the sash.

With these objects in view, my invention consists in the novel features of construction hereinafter described, pointed out in the 45 claim and shown in the accompanying drawings, in which:

Figure 1 is a detail perspective view of a portion of a window frame and sash, partly broken away, showing the application of my improved sash lock. Fig. 2 is a perspective view of my improved lock detached. Fig. 3 is a vertical section through the same. Fig. 4 is a transverse section.

Referring to the drawing A indicates a window frame and B a sash mounted there- 55 in, the above description being given so

that the operation of my improved lock can be readily understood.

In carrying out my improved invention, I employ a casing C which is adapted to be arranged within a recess formed in the edge 60 of the side bar of the sash B, said recess having a bore communicating therewith which extends out through the side bar as clearly shown and adapted to receive the locking bolt of my improved lock as will 65 be hereinafter fully described. The casing C is provided with an open side which is closed by a plate K secured to the casing by screws or the like in order that the same can be removed to facilitate the insertion of 70 the locking members which will be herein-after fully described. A face plate D is formed integral with the casing of a greater length than the casing, the ends of which extend out above and below the same and 75 have openings formed therein through which screws are adapted to pass for securing the same within the recess of the sash, it of course being understood that the face plate is countersunk in the edge of the sash. 80 The face plate D is provided with a square opening through which extends a substantially square locking bolt E which is mounted in a groove F formed in one side of the casing and extends out through the rear end 85 of the casing through an opening formed therein which communicates with the bore formed in the sash and said bolt is of such a length that it will extend out beyond the inner edge of the side bar of the casing at such a distance 90 that it can be readily grasped by the fingers so as to operate the same. For normally holding the sliding bolt E outwardly so that it will engage the window frame or be forced into a recess formed therein, I pro- 95 vide a spring G which is substantially U-shaped having a coil G' which is arranged over a stud pin H extending inwardly from one of the sides of the casing, said spring being provided with legs of different 100 lengths, the longer leg extending through a slot E' formed in the bolt so that the tendency of the spring is to force the bolt outwardly at all times. For locking the bolt E against the ten- 105 sion of the spring G so that the same will be out of engagement with the frame, I bifurcate the inner end of the bolt as clearly shown at I and in said bifurcation I mount a pivoted locking member J which is pro- 110

vided with a head J' extending outwardly beyond the end of the bolt as clearly shown, and by drawing down on the head J' of the locking member when the bolt is drawn inwardly, the notched end of the locking member will be forced outwardly so that when the bolt is released it will engage the edge of the casing adjacent the opening through which the bolt extends, it of course being understood that the bore in which the bolt slides is of such a size that it will allow the locking member to move upwardly. By notching the inner end of the locking member the upward and downward movement of the same is limited as the inward movement of the locking bolt is limited by the spring in such a manner that it is impossible to draw the bolt inwardly beyond the end of the locking member and by this arrangement when the locking member is forced upwardly the reduced portion of the locking member is brought into engagement with the back of the casing so as to limit the upward movement of the same. When it is desired to release the bolt so as to allow the same to be thrown inwardly by the spring in order to lock the sash in the desired position, by simply pressing upwardly on the head J' the locking member J will be thrown out of engagement or down into the bifurcation of the bolt so as to allow the spring to force the bolt inwardly.

From the foregoing description, it will be seen that I have provided a sash lock

which is provided with a sliding spring actuated bolt having means for locking the bolt within the casing against the tension of the spring so as to hold the same out of engagement with the frame of the window in order to allow the sash to move freely up and down within the casing, said locking member being so mounted within the bolt that in order to release the same, it is only necessary to press upwardly on the head of the locking member.

Having thus fully described my invention, what I claim as new and desire to secure by Letters Patent, is:

A sash lock comprising a casing having integral apertured ears, and provided with a removable side plate, said casing being provided with apertured ends, a stud pin secured to the inside of said casing, a bolt slidably mounted on the apertures of said casing and provided with a bifurcated end portion, a U-shaped spring having a coil portion arranged over said stud pin, and having one of its ends extending into the bifurcation of said bolt, the walls of said bolt being apertured at its end, and a locking member J pivotally mounted on a pin arranged in said apertures having a head portion and provided with a notched end adapted to co-act with the end of said casing.

WARREN B. WEAVER.
